UNITED STATES PATENT OFFICE.

ISAAC H. MILLIKEN, OF ASPINWALL, PENNSYLVANIA, ASSIGNOR TO McCONWAY & TORLEY COMPANY, OF PITTSBURGH, PENNSYLVANIA, A CORPORATION OF PENNSYLVANIA.

ANTITELESCOPING DEVICE FOR RAILWAY-CARS.

1,148,038.

Specification of Letters Patent. Patented July 27, 1915.

Application filed June 24, 1914. Serial No. 846,964.

To all whom it may concern:

Be it known that I, ISAAC H. MILLIKEN, a citizen of the United States, residing at Aspinwall, in the county of Allegheny and State of Pennsylvania, have invented certain new and useful Improvements in Anti-telescoping Devices for Railway-Cars; and I do hereby declare the following to be a full, clear, and exact description of the invention, such as will enable others skilled in the art to which it appertains to make and use the same.

My invention relates to safety appliances for railway cars and has for its object the prevention of telescoping of the cars when trains are in collision. As is generally understood, telescoping rarely occurs unless there is such a vertical shifting or displacement of the cars with respect to each other that the mating platforms, buffers, end sills or the like are forced out of alignment to an extent enabling them to pass or ride by or over each other.

Accordingly, it is the object of my invention to provide simple, efficient and practical means for preventing adjacent platforms, buffers, end sills or the like from passing each other in the direction of length of the train when the cars are coupled to one another. Generally stated, this object is accomplished by providing the car coupler with inclined means adapted to extend under a similarly inclined portion of an adjacent car during maximum buffing stresses and to engage such portion of the adjacent car upon a relative vertical movement of the said car and coupler, to thereby restrain and limit the vertical movements of connected cars to an extent sufficient to prevent the opposed faces of mating platforms, buffers or end sills, as the case may be, from becoming wholly disengaged and riding over or sliding past each other in the direction of length of the cars.

As my invention is conspicuously advantageous when employed for the purpose of preventing the telescoping of passenger cars, it has been illustrated in the accompanying drawings in a form that is especially applicable to cars which are provided with buffers, since passenger cars generally are provided with buffers in addition to the yieldingly supported car couplers.

In the drawings illustrating my invention, the scope whereof is pointed out in the ap-

pended claims, Figure 1 is a view showing my invention as applied to two passenger cars, the cars being in normal coupled relation, the couplers being shown in side elevation and the buffers and platform end castings being in vertical section. Fig. 2 is a view corresponding to Fig. 1, but illustrating the relations assumed by the parts when the buffers and draft gears are fully compressed and in normal alignment. Fig. 3 is a view similar to Fig. 2, but showing the relations of the parts when the buffers and draft gears are compressed and one car is in the position of maximum elevation with respect to the adjacent car. Fig. 4 is a plan view of the devices at the end of one of the cars, the coupler and buffer being compressed; and Fig. 5 is a view corresponding to Fig. 3, but illustrating a modification of some of the structural details of my invention.

In the drawings, 1 indicates a coupler of the Master Car Builders' type having a knuckle which is provided at its exposed end with an upwardly extending projection 2 that is adapted, as illustrated in Fig. 3, to engage a corresponding portion 3 of the end casting of the opposite car platform to limit the relative vertical movements of the opposed platforms, as will be readily understood. In order to better insure the secure engagement of the tops of the lugs 2 of the coupler knuckles with the undersides of their respective platform end castings when the cars are shifted vertically during a collision, the upper face of each lug 2 and the under face of each portion 3 of the end casting are preferably correspondingly inclined or beveled as shown, the inclined face of the knuckle sloping downwardly toward the knuckle-pin 4; and in order to secure an extended and even bearing of the coupler upon the appropriate face 3 of the opposed end casting, the upper face of the upper pivot lug of the coupler head may be beveled, as at 5, so as to form a continuation of the inclined face of the knuckle 2. Except as above indicated the construction of the car coupler 1 is not of material importance and, therefore, requires no further description.

In both forms of construction illustrated in the drawings a buffer is slidably mounted on the end casting of the platform. In the construction shown in Figs. 1, 2, 3 and 4, in which the lower member of the end casting

preferably extends to or approximately to the line of the front vertical face of the buffer when the latter is in its position of complete compression, the inclined surface 5 of the upwardly extending projection 2 on the knuckle together with the inclined upper face 5 of the pivot lug of the coupler on the adjacent car are adapted to directly engage the under surface of the portion 3 of the end casting; but in Fig. 5 is shown an arrangement of parts in which the coupler is designed to engage the under surface of the buffer of an opposed car, the upward movement of the coupler being, however, resisted by the platform end casting to which is transmitted the upwardly acting forces imparted to the buffer by the coupler.

In the construction shown in Figs. 1 to 4, inclusive, of the drawings the end casting or 20 end member 6 of the platform is illustrated as provided with a downwardly extending projection 7 to which the usual carry-iron 8 for supporting the coupler is secured, such form of construction being preferred on account of its simplicity.

The buffer 9, which is slidably mounted on the end casting or end sill member 6, is preferably provided upon its rear or inner side with a pocket 10 for the reception of a central buffer stem 11, the side walls 12 of the pocket being divergent rearwardly, as illustrated in Fig. 4, so as to permit the buffer 9 to turn freely when the car is passing around a curve; and side or lateral buffer stems 13 are also preferably employed, a well known form thereof being shown in the drawing. The buffer 9 is also formed with jaws affording a recess 14 into which the top member 15 of the platform end casting 6 fits, while the lower face 16 of the buffer is preferably inclined to correspond to the adjacent inclined portion 3 of the end casting, such a construction, as will be appreciated from an inspection of Fig. 3 of the drawings, serving to distribute and equalize such strains as may be imparted to the end casting by the opposed coupler on the adjacent car at the time of a collision. The usual foot plate rests upon and extends between the buffer 9 and the platform end casting 6.

In the form of my invention illustrated in Fig. 5 the buffer 9^a is shown as slidably mounted on a platform end casting or end sill 6^a. The lower face of the buffer is inclined, as at 16^a, and is designed to come into direct engagement with the correspondingly inclined faces of the knuckle 2 and pivot lug 5 of the opposite coupler on the adjacent part. The buffer 9^a is also provided with a centrally disposed, rearwardly extending arm or member 17 that extends under the platform end casting 6^a in sliding engagement therewith; and for a similar purpose, namely, to efficiently resist upward forces delivered by the adjacent coupler on the op-

posed car, the buffer 9^a is also preferably formed with a rearwardly extending central projection 18 which slidably fits into a corresponding opening or pocket 19 that is formed in the forward end of the end casting 6^a. In this form of construction, instead of fashioning the central projection with a recess for the reception of a central buffer stem, as is the case in the construction illustrated in Figs. 1, 2, 3 and 4, the lug 18 is, for the sake of adding to the strength of the apparatus, preferably formed as a solid member.

In the following claims the term end sill member is employed in a generic sense, and comprehends not only an end sill, but also members which are the equivalents thereof for the purposes of this invention, such as buffers, platform end castings or like devices at the end of the car independent of the coupler.

I claim:

1. In a device of the character indicated, the combination with a car, of a coupler which is located beneath said car and which projects beyond the end thereof in all buffering positions, said coupler being provided toward its forward end with an inclined portion which is adapted to engage a correspondingly inclined under face of the end portion of an opposite car to thereby prevent the opposed end sill members of adjacent coupled cars from separating vertically and subsequently moving past each other in the direction of length of the cars. 100

2. In a device of the character indicated, a coupler having on its head a rearwardly and downwardly extending beveled portion which is adapted to engage an end sill member of an adjacent car. 105

3. In a device of the character indicated, an end sill member fixed vertically with respect to the car and having a beveled face which is adapted to be engaged by an upwardly extending portion of the coupler of an adjacent car. 110

4. In a device of the character indicated, a coupler having a knuckle which is provided at its outer end with an inclined top face which is contiguous to and extends from the pivot lugs of the coupler head and which is adapted to engage an end sill member of an adjacent car. 115

5. In a device of the character indicated, a coupler having an upper pivot lug which is provided with an inclined top face, and having a knuckle which is provided at its outer end with an inclined top face, the said inclined faces sloping in the same direction and being in substantially the same 120 plane. 125

6. In a device of the character indicated, the combination with a platform end member, of a buffer which is mounted thereon so as to slide longitudinally with respect there- 130

to, said end member having on its under side an inclined portion which is adapted to engage a coupler on an adjacent car.

7. In a device of the character indicated, 5 the combination with a platform end member, of a buffer member slidably mounted thereon, said buffer member having on its lower side an inclined face which is adapted to project over the coupler of an adjacent 10 car, member being adapted to have interfitting engagement with said buffer and platform end member, one of said members being adapted to engage and limit the upward movement of the said coupler of the 15 adjacent car.

8. In a device of the character indicated, the combination with a platform end member which is rigidly mounted on a car and is formed with an inclined face on its lower 20 side, of a buffer slidably mounted thereon, the lower side of said buffer being in engagement with said platform end member and the lower portion of said platform end member extending substantially to the forward 25 face of the buffer when the latter is fully compressed, and said inclined face being adapted to be engaged by a coupler on an adjacent car.

9. In a device of the character indicated, 30 the combination with a platform end member which is provided with a beveled portion that is adapted to be engaged by a coupler on an adjacent car, of a buffer slidably mounted on said end member and having a correspondingly inclined lower face. 35

10. In a device of the character indicated, the combination with a coupler having the upper surface of its knuckle inclined downwardly from its forward edge toward the knuckle-pin, of an end sill device above 40 said coupler, said end sill device having an inclined face corresponding to the said inclined face of said knuckle, the inclined face of said knuckle being adapted to engage an end sill device of an adjacent car, and the 45 inclined face on said end sill device first named being adapted to engage a portion of a coupler on an adjacent car.

In testimony whereof I affix my signature, in the presence of two subscribing witnesses. 50

ISAAC H. MILLIKEN.
